PYROPHORIC LIGHTING MECHANISM

Louis V. Aronson, Newark, N. J.

Application March 1, 1930, Serial No. 432,363

2 Claims. (Cl. 67—7.1)

My invention relates to pyrophoric lighting mechanism and to a combined device including mechanism of that character and also including a receptacle for cigarettes, cigars or the like, hereinafter generically termed "cigarettes".

My invention, in one of its phases, relates to pyrophoric lighting mechanism per se and particularly to novel arrangements of some of the parts thereof.

Various other objects, advantages and characteristics of my invention will become apparent from the following description taken in connection with the accompanying drawing.

My invention resides in the pyrophoric lighting mechanism, combined features, arrangements and details of construction of the character hereinafter described and claimed.

For an illustration of one of the forms which my invention may take, reference is to be had to the accompanying drawing in which:

Figure 1 is an elevational view of the front surface of a combined pyrophoric lighter and cigarette container;

Figs. 2 and 3, respectively, are elevational views of the side surfaces of the device shown in Fig. 1;

Fig. 4 is a plan view of the device shown in Figs. 1, 2 and 3;

Fig. 5 is a vertical sectional view, partly in elevation, and is taken substantially on the line 5—5 of Fig. 1 looking in the direction of the arrows;

Fig. 6 is a vertical sectional view, partly in elevation showing the device of Figs. 1, 2 and 3 with a cigarette receptacle in open position; and

Fig. 7 is a perspective view, in part disassembled, of parts of the operating means for the lighter mechanism.

Referring to Figs. 1-7, C represents a fuel casting container or receptacle for pyrophoric lighting mechanism of any suitable character and C₁ represents a casing, container or receptacle adapted to receive a plurality of cigarettes A.

The casing C comprises a bottom wall 1 and a top wall 2, suitable side wall structure joining said walls 1 and 2 and herein shown as comprising end walls 3, 3 disposed in parallel relation, if desired, but not necessarily, Fig. 6, and front and rear walls 4, 4 disposed somewhat in converging relation, if desired, but not necessarily, Fig. 5.

Carried by the wall 2 is an upstanding wick tube 5 through which and said wall 2 a wick 6 extends to the interior of the casing C. Coactable with the wick tube 5 is a snuffer cap 7 carried by a suitable snuffer-cap-carrying member 8

which, in the example shown although not necessarily, is shaped somewhat as an inverted receptacle and comprises depending, spaced side walls 8a, 8a, Fig. 5.

The member 8 is pivoted for oscillatory movement on a pin or axle 9 supported in any suitable

manner above the top wall 2 of receptacle C. As herein illustrated and preferably but not necessarily, there upstands from the top wall 2 wall structure 10 of suitable configuration. Said wall structure 10 is open at the top for the reception of the member 8 and the hereinafter described operating member therefor and forms a chamber in which these members, particularly the latter, are received. The aforesaid pin 9 is carried, preferably, by spaced standards 11, 11, Fig. 10, upstanding from the top wall 2 and disposed interiorly of the wall structure 10 approximately midway between the ends thereof.

Freely rotatable on the pin 9 between the depending walls 9a, 9a of member 9 is a wheel 12 having a serrated or roughened peripheral face for coaction with a pyrophoric element 13 projecting from a tube 14 extending through the casing C. A spring 15 is disposed within the tube 14 and biases said pyrophoric element 13 into engagement with the wheel 12, the spring 15 being maintained under suitable tension, as by a headed screw 16 coacting therewith and threaded into an opening in the bottom wall 1 of casing C.

Rotatable as a unit with the wheel 12 is a ratchet wheel 17 by which uni-directional rotative movement is imparted to the wheel 12, as hereinafter described.

Any suitable form of mechanism may be utilized for operating the aforesaid wheels 12 and 17, and for swinging the member 8 about its axis to elevate the snuffer cap 5. As herein disclosed, a manually actuatable knob 18 is utilized for this purpose, said knob 18 being carried by a member 19 reciprocator in a barrel member 20 open at its top and depending into the casing C, said knob 18 and member 19 being biased in an upward direction, Fig. 6, by a helical spring 21 disposed in said barrel member 20.

The knob 18 comprises spaced, vertically extending members 18a, 18a extending toward the pin 9 and formed at their ends with racks which mesh, respectively, with pinions 22, 22 freely rotatable on the aforesaid pin 9.

In accordance with a feature of my invention, the pinions 22, 22 are of greater thickness than the members 18a, 18a which are associated, respectively, therewith and said pinions 22, 22 are disposed, respectively, in permanent meshing relation with toothed segments 8b, Fig. 7, formed in each depending wall 8a of the member 8, said toothed segments 8b being disposed near the end of said member 8 removed from the snuffer cap 7.

With the parts in assembled relation, the pinions 22, 22 are disposed immediately adjacent the respective standards 11, 11 on the interior surfaces thereof as illustrated particularly in Fig. 5. Between the pinions 22, 22, the wheels 12 and 17 are disposed, the pin 9 passing through all of said pinions and wheels to form the pivotal axis 60.

therefor. When thus arranged, the racks at the ends of the members 18a, 18a mesh, respectively, with the pinions 22, 22, each of the latter being maintained in permanent meshing relation with a toothed segment 8b of the member 8. Accordingly, when the knob 18 is depressed, the member 8 is swung in a clockwise direction, Fig. 6, and when said member 18 rises under the influence of spring 21, the member 8 returns to its normal position such as indicated in Fig. 6 where the snuffer cap 7 coats with the wick tube 5 to form a housing for the upper end of wick 6.

Any suitable arrangement may be utilized for operating the wheels 12 and 17 in response to depression of the knob 18. In the example shown but not necessarily, there is thus utilized a member 23 having a resilient extension 23a coactable with the ratchet wheel 17. As herein illustrated, the member 23 is secured to the member 8 and 10 interiorly thereof by the stem of the snuffer cap 7 which passes through both of said members and is headed exteriorly of said member 8.

Accordingly, when the knob 18 is depressed to produce clockwise movement of member 8, Fig. 6, 20 the ratchet wheel 17 and serrated wheel 12 are rotated in a similar direction due to the pawl-like engagement effected between the extension 23a of member 23 and the ratchet wheel 17. As a result, the serrated face of wheel 12, by coaction with the pyrophoric element 13, produces a shower of sparks which are directed toward the now exposed end of wick 6 to ignite the fuel carried thereby and produce a flame which may be utilized for any suitable purpose. When the 30 member 8 moves in a counter-clockwise-direction, Fig. 6, under the influence of the rising knob 18, the extension 23a of member 23 idles with respect to the ratchet wheel 17, the wheels 12 and 17, accordingly, remaining stationary 40 particularly because the pyrophoric element 13 is biased into engagement with said wheel 12.

Fuel of any suitable character, either solid, 45 semisolid or liquid may be introduced into the casing C in any suitable manner. If desired and as illustrated, one end wall 3 of said casing C may be provided with a perforation threaded for the reception of a plug or cap 24 which, when removed, permits the introduction of fuel interiorly of said casing C, the latter, if desired, containing a mass 25 of suitable material, as cotton, 50 for absorbing the fuel.

In accordance with my invention, the herein described container C1 comprises mating sections R, Ra, each adapted to contain a plurality 55 of cigarettes A. Each of these sections may be and preferably is of open, receptacle-like configuration, the section R, preferably, being formed integrally with the casing C. When thus formed integrally, it is desirable that the bottom wall 60 26 of section R be formed substantially as a continuation of the rear wall 4 of casing C and that the end walls 27, 27 thereof be formed substantially as continuations respectively of the end walls 3, 3 of said casing C, said end walls 27, 65 27 being joined by a wall 28 to complete the section R.

The section Ra conforms substantially with the section R and, therefore, comprises a bottom wall 29, end walls 30, 30, said end walls being joined by a lower wall 31 and an upper wall 31a.

Preferably, the section Ra is pivoted to the section R, such pivotal arrangement being constituted by any suitable mechanism. For this pur-

pose and as herein illustrated, the adjacent walls 27 and 30 of the respective sections R and Ra may be provided with sets of spaced perforated ears which are brought into alignment and connected together by a pin or member 32 which passes through all of said ears. When the section Ra is closed upon the section R, the end walls 30, 30 thereof come into alignment with the end walls 27, 27 of the section R; similarly, the lower wall 31 of section Ra comes into alignment with the lower wall 28 of section R while the upper wall 31a of said section Ra fits snugly beneath the bottom wall 1 of the fuel casing, Fig. 5. Any suitable mechanism may be utilized for retaining the sections R, Ra in closed position. As herein shown, there is utilized for this purpose a spring latch 33 carried by the section R and having a part coacting with the section Ra.

As herein shown, it is desirable that the cigarettes A be releasably retained in each of the sections R and Ra. For this purpose, there may be associated with the respective sections R and Ra members 34, 34a preferably of sheet-like, light-weight resilient material, said members being disposed for pivotal movement about the pin 32. 25 Preferably each of the members 34, 34a is biased into engagement with the cigarettes A in the respective sections and for this purpose, springs 35, 35a may be coiled about the pin 32 and associated with the respective members 34, 34a each 30 spring having an end which, as illustrated, engages and biases the associated member 34 or 34a in the proper direction.

The receptacle Ra, preferably, is biased to open position with respect to the receptacle R and, for this purpose, the aforesaid springs 35, 35a may be utilized, the arrangement being such that movement of the section Ra to closed position causes said springs to be wound or energized.

The herein described casing structure is formed 40 of any suitable material; usually, however, sheet material, particularly sheet metal is employed and it is desirable, although not necessary, that visible surfaces be suitably plated or otherwise ornamentally finished.

While the invention has been described with respect to a certain particular preferred example which gives satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. Pyrophoric lighting mechanism comprising a lever, a member on which said lever is pivoted, and means for oscillating said lever, said means comprising a movable rack member, and a pinion on said first-named member, said rack member coacting with said pinion, the teeth of said pinion interlocking with said lever.

2. Pyrophoric lighting mechanism comprising a lever, a member on which said lever is pivoted, and means for oscillating said lever, said means comprising a movable rack member, and a pinion on said first-named member, said rack member coacting with said pinion, said lever comprising a toothed segment with which the teeth of said pinion interlock.
